US0D1082528S

(12) **United States Design Patent** (10) **Patent No.:** **US D1,082,528 S**
(45) **Date of Patent:** **** Jul. 8, 2025**

(54) **LID FOR A STORAGE CONTAINER**

(71) Applicant: **SWIMC LLC**, Cleveland, OH (US)

(72) Inventors: **Michael P. Yajko**, Peninsula, OH (US);
Eugene M. Merrill, Brunswick, OH (US)

(73) Assignee: **SWIMC LLC**, Cleveland, OH (US)

(***) Term: **15 Years**

(21) Appl. No.: **29/943,089**

(22) Filed: **May 20, 2024**

CLAIM

The ornamental design for a lid for a storage container as shown and described.

DESCRIPTION

FIG. 1 is a top perspective view of a lid for a storage container showing our new design;

FIG. 2 is a front view of the lid for a storage container shown in FIG. 1;

FIG. 3 is a rear view of the lid for a storage container shown in FIG. 1;

FIG. 4 is a left side view of the lid for a storage container shown in FIG. 1;

FIG. 5 is a right side view of the lid for a storage container shown in FIG. 1;

FIG. 6 is a top view of the lid for a storage container shown in FIG. 1; and,

FIG. 7 is a bottom view of the lid for a storage container shown in FIG. 1.

The broken lines and any unshaded regions within the broken lines illustrate portions of the lid for a storage container that form no part of the claimed design.

1 Claim, 5 Drawing Sheets

Related U.S. Application Data

a continuation of application No. 29/776,261, filed on Mar. 29, 2021, now Pat. No. Des. 1,012,730.
